UNITED STATES PATENT OFFICE

2,501,743

BOTTOM-DUMP HOPPER

Eugene W. Schellentrager, Shaker Heights, Ohio,
assignor to The Atlas Bolt & Screw Company,
Cleveland, Ohio, a corporation of Ohio

Application June 9, 1945, Serial No. 598,616

2 Claims. (Cl. 222—503)

1

This invention relates to door or bin gate mechanism for bottom dump hoppers.

One object of the invention is to provide improved mechanism of this kind adapted particularly for use with iron pigs, scrap iron or steel, or other similar material usually difficult to handle with dumping doors, although the invention is useful with any material.

Another object is to provide improved dumping mechanism in which the doors are mounted to swing away from instead of across the openings which they close, and also by motion around centers which not only are considerably above the doors themselves but also widely separated for the two doors, thereby adapting the doors for free and unimpeded motion produced by the load when dumping, and materially reducing the labor of closing them.

Still another object is to provide improved operating mechanism for dumping doors of the character described, including simple but very efficient linkage connecting the doors to each other and to the operating device, and including toggle members for releasably locking the doors closed.

Finally, another object is to provide improved door operating mechanism including counterweight means effective upon both doors and with varying effects in different door positions, all for the purpose of enabling the doors to be operated manually, by simple operations, and without requiring unusually heavy strain.

Further objects of the invention in part are obvious and in part will appear more in detail hereinafter.

Referring to the drawings,

Fig. 1 represents a front elevation of one form of mechanism embodying the invention, the doors being shown in closed position;

Fig. 2 is a similar view showing the doors in open position;

Fig. 3 is a plan view, corresponding to Fig. 1, certain parts being omitted;

Fig. 4 is an end elevation; and

Fig. 5 is a detail view of a ratchet device.

The present invention contemplates a hopper or receptacle for containing material and having a bottom normally closed by dump doors, all for the purpose of receiving and holding a mass of material intended for delivery for any desired purpose, such as material to be charged into a car or bucket and then into a furnace, cupola or the like. While it may be used in handling any kind of material, such as ore or other granular substance, it is more particularly de-

2

signed for use in the handling of masses of iron or steel, such as pig iron, scrap metal, or the like. Such material is usually difficult to handle in dumping hoppers of this type by reason of the pressure of the material on the doors and the tendency to interfere with their opening and to restrain them in closed position, requiring heavy effort, even the use of the power mechanism, for operating the doors. The present invention provides improved mechanism for handling material of this kind, but it nevertheless is capable of operation manually without unduly taxing the operator, either in release of the doors to permit them to move by gravity and weight of the load to open position, or for returning them to closed position.

The invention may be embodied either in a stationary hopper which discharges, for example, into a weighing scale car, or which itself includes or forms a part of weighing mechanism, the load being dumped into any suitable receptacle, or the hopper itself may form part of scale mechanism mounted upon a car by which the material is transported to the desired location, say to the skip hoist of a blast furnace.

The drawings show a stationary installation, 10 indicating a suitable support which here is a portion of the roof of a building in which the hopper is mounted in such manner that iron pigs, for example, can be picked up by a crane and a magnet (not shown) outside the building and deposited in the hopper for delivery to a car or upon a weighing scale beneath it. The structure includes a generally rectangular frame 11, made of suitable structural steel shapes, mounted upon the roof or other support 10. Depending from the frame 11 is the hopper 12, which may be of any suitable shape in plan, such as round or square. It is shown as round and of inverted frusto-conical form, having a top opening 13 at floor level and having its bottom cut off on two inclined planes intersecting along a diameter, to form a bottom opening the opposite edge portions of which, marked 14, are of semi-elliptic form, because sections of a cone, and may be reinforced in any suitable manner, to provide bearing surfaces or seats for the doors. There are two doors 15, each made of sheet metal plates mounted on a structural steel frame. They are preferably of rectangular shape in plan view, although the opening which each closes is semi-elliptical, because the rectangular form is more convenient to construct and to manipulate. Each of the two doors is mounted upon two parallel platelike wings 16 pivoted upon horizontal

axes 17 which are located considerably above the level of the doors themselves, the axes for the two doors being relatively widely spaced apart. As shown, the two pivots 17 are only slightly below the upper end of the hopper, and each is directly above an outer edge of its door, when the door is closed, as shown in Fig. 1.

The operating mechanism for the doors includes a shaft 18 mounted in a suitable support 19 and capable of being rotated at will, in either direction, by manipulation of reversible ratchet mechanism, marked generally 20, and actuated by hand lever 20a. The ratchet mechanism is more or less conventionally shown in Fig. 5 because any reversible ratchet mechanism which includes a manually operable trigger or other control device 21, by means of which its direction of operation may be reversed, is suitable for the purpose, the details thereof forming no part of the present invention.

Shaft 18 extends in a direction parallel to the axes about which the two doors swing. At each end, said shaft is provided with connections to suitable link mechanism for operating the doors, two such sets of linkage being employed to equalize or balance the stresses. Each mechanism includes oppositely extending arms 22, 23 fast on said shaft and connected respectively by links 24, 25 to the two doors 15, the arrangement being such that when shaft 18 is rotated in one direction, the two doors simultaneously move toward open position, shown in Fig. 2, and when said shaft is rotated in the opposite direction, they move toward the closed position shown in Fig. 1.

The doors are preferably also provided with suitable counterweight mechanism, such as arms 26 loosely mounted to turn upon the shaft 18 and each connected by a link 27 to one of the supporting wings 16 for one of the doors 15. On each arm 26 is adjustably mounted a heavy counterweight 28. Since the two doors 15 are interconnected by means of the links 24, 25 and the arms 22, 23, the counterweights are effective simultaneously upon both doors. A single arm and counterweight may be employed, although two sets are shown, one at each end of shaft 18, as indicated in Fig. 4.

The apparatus described operates as follows:

Fig. 1 illustrates the parts in door closed position. Link 24 and its operating arm 22, together, form a toggle connecting shaft 18 to one of the door supporting wings. The knuckle 29 of said toggle, in door closed position, lies just above and beyond dead center, i. e., above a line connecting the center of shaft 18 to the center of the pivotal connection of link 24 to the wing 16. Likewise, arm 23 and link 25 form a toggle, the knuckle of which is also slightly beyond dead center. Further, rotation of shaft 18 in the counterclockwise direction, Fig. 1, beyond approximately the position of the parts shown, is prevented by said shaft, which lies directly beneath links 25 and forms an obstruction to prevent further downward motion thereof. While the counterweights and their arms are connected to the doors by links 27, these parts do not interfere with some slight motion of the ends of the arms 22 and 23 back and forth across dead center in door closed position, because the ends of said arms are moving in substantially vertical paths and the closed doors prevent counterclockwise movement of arms 26. The result is that as the doors reach closed position the outer ends of the arms 22, 23 can be sprung across dead center position to the position shown in Fig. 1,

where the doors are releasably locked in closed position by a toggle effect. The weight of a load upon the doors cannot start door opening movement.

5 A charge of material, for example, pigs of iron, is dumped into the open end of the hopper from which the cover (not shown) has been removed, until a sufficient charge has thus been collected. When it is desired to dump the load, the operator, having adjusted the ratchet trigger 21 to the proper position, grasps the operating handle 20 and turns shaft 18 in the clockwise direction Fig. 1, to break or start opening the toggle. This requires no more than reasonable effort of an ordinary operator. As soon as the toggle knuckles 29 move downwardly sufficiently to pass beyond dead center, the weight of the load completes door movement to fully open position, as shown in Fig. 2, but if the doors do not completely open of themselves, that motion can be completed by further manual operation of the ratchet.

20 To close the doors, the operator reverses the operating direction of the ratchet mechanism, grasps the handle 20 and turns the shaft 18 in the opposite direction, counterclockwise in Fig. 2, and by one or more operations of the ratchet lever mechanism returns the doors to their original closed position.

25 It will be noted that as the doors open and close they do not slide along the surfaces around the edges of the doors against which they bear, but they leave and approach such surfaces breastwise or flatwise, with motion of translation rather than a hinging effect, such as that of the ordinary door. That is because the doors are flat, with their upper surfaces lying in a straight plane, and the pivotal axes around which the doors swing are rather remote from or external to the doors themselves, and in this case lie above the doors and outwardly beyond their centers of gravity when they are closed, and more specifically in vertical alignment with their outer edges when they are closed. Furthermore, the two pivotal axes are widely separated rather than close together. Consequently the doors open by more or less horizontal motion, although, of course, their outer edges move up while their inner edges move somewhat downwardly. Their centers of gravity, indicated at A, Figs. 1 and 2, swing back and forth from one side to the other, about the pivotal axis. This door motion enables the weight and the movement of the load to materially assist in producing the opening effect.

30 It will also be noted, by comparison of Figs. 1 and 2, that each door as a whole swings from a position at one side of its pivotal axis to a position on the other side of said axis. The same door motion produces motion of the counterweight from one side to the other side of the axis about which the counterweight moves, bent always in opposition to the motion of the doors themselves. Thus, the counterweight effect is always balanced against door weight in any door position. By suitable adjustment of the counterweights along their arms, they may be made to almost exactly balance the weight of the doors, so that they are stable and will stay put in practically any position to which they may be adjusted. That condition, also, is responsible in large measure for reducing the effort required to move the doors manually, enabling them to be either broken open to release a load, or to be moved completely from full open to closed position, by an effort within the strength of any ordinary operator.

Finally these doors are effective in handling heavy material in large masses, such as scrap iron, pig iron or other metal masses, which ordinarily tend to dig into the doors and prevent them from opening. Not only does the weight of the material assist in producing door opening movement, but also the doors are so mounted that they move, or can be moved, quite readily to a position in which they are entirely out of the path of the material being discharged and thus out of the way of injury. Thus they are strong, durable and not likely to get out of order in service.

Other advantages of the invention will be apparent to those skilled in the art.

What I claim is:

1. Apparatus of the character described, comprising a hopper having a bottom opening the edges of which lie in two planes which intersect along a diametrical line and are inclined upwardly and outwardly from the intersection, two straight surfaced doors for said opening which meet edge to edge at the line of intersection when the doors are closed with their surfaces in said planes, pendular arms supporting said doors for swinging motion about parallel axes lying above them and so spaced apart that when the center of each door is directly beneath its pivotal axis the door lies substantially midway between closed and open positions, link and lever mechanism connecting said doors for simultaneous and like movement toward and from each other, a counterweight, an oscillating arm carrying said counterweight, and a link operatively connecting said arm and said doors, said link being of such length and so arranged that as said doors move back and forth across their axes of oscillation the counterweight moves likewise but always in opposition to door motion, whereby the counterweight always tends to stabilize and maintain the doors in any position to which they may be moved and thus minimizes the effort required to move them in either direction.

2. Apparatus of the character described, comprising a hopper having a bottom opening the edges of which lie in two planes which intersect along a diametrical line, two straight surfaced doors for said opening which meet edge to edge with their upper surfaces in said planes and inclined upwardly and outwardly from said line of intersection when the doors are closed, pendular arms supporting said doors for swinging motion about parallel axes lying above them and so spaced apart that when the doors are closed the outer edge of each lies directly beneath its pivotal axis and when half open its center lies substantially midway between door-closed and door-open positions, a shaft rotatable upon an axis parallel with but below the axes about which the doors swing, opposed cranks fast on said shaft, links connecting said cranks to said doors for causing simultaneous and like movement of the doors toward and from each other, a counterweight member mounted to swing about the axis of said shaft, and a link operatively connecting said counterweight to said doors, said link being disposed in such manner that the moment of inertia of the counterweight about the shaft axis always substantially balances the moments of inertia of the doors about their axes in any position to which the doors may be moved.
